UNITED STATES PATENT OFFICE

2,614,693

AMALGAMATOR

Leonello Brunetti, Mountain View, Calif.

Application January 27, 1948, Serial No. 4,600

1 Claim. (Cl. 209—205)

1

This invention relates to improvements in amalgamators.

An object of the invention is to provide an improved amalgamator construction for separating and collecting gold from gold-containing ore pulp.

Another object of the invention is to provide an improved amalgamator including an elongated trough formed with a bottom which slopes inwardly and downwardly from its opposite ends to a central low point connected by means of a valved fitting to a retort, and rotatable means in said trough for separating the gold from the ore pulp fed into the trough, combining the same with mercury contained in the lower portion of the trough for collecting the separated gold in a pot supported by and connected with said retort, while the tailings are discharged from the outlet end of said trough.

A further object of the invention is to provide an improved construction of amalgamator comprising an elongated separating trough having an inwardly and downwardly sloping bottom tapering from its opposite ends and connected with a valve-controlled retort, said trough being adapted to contain mercury for separating gold from the gold ore pulp fed into one end of the trough, and said trough being adapted to support various forms of single or dual power driven screws for pulverizing and separating gold from the tailings which will be discharged from the end of the trough remote from its feed or loading end.

Another object of the invention is to provide an improved construction of amalgamator which will include a separating trough, a retort, means for heating the retort for vaporizing the mercury contained therein, and a condenser for cooling the volatilized mercury and for discharging it back to the amalgamator trough.

A still further object of the invention is to provide an improved amalgamator which will be highly efficient in operation and relatively inexpensive to manufacture and produce.

With the foregoing and other objects in view, which will appear as the description proceeds, the invention consists of certain novel details of construction and combinations of parts, herein-after more fully described and pointed out in the claim, it being understood that changes may be made in the construction and arrangement of parts without departing from the spirit of the invention as claimed.

Referring to the drawings:

Figure 1 is a longitudinal vertical sectional view through the improved amalgamator.

2

Figure 2 is a sectional view taken on the line 2—2 of Figure 1.

Figure 3 is a transverse sectional view through the amalgamator trough showing the use of two separating screws of similar size.

Figure 4 is a transverse sectional view through the amalgamator trough showing the use of two separating screws of dissimilar size.

Figure 5 is a transverse sectional view through the amalgamator trough showing the use of a single separating screw and a cooperating endless chain separator.

Figure 6 is a sectional view taken on the line 6—6 of Figure 5.

Like characters of reference are used throughout the following specifications and the accompanying drawings to designate corresponding parts.

In carrying out the invention, there is provided an improved amalgamator having an elongated substantially U-shaped trough generally designated by the reference numeral 1 formed with oppositely disposed parallel side walls 2 and 3, and a closed end wall 4. A feed chute 5 is supported adjacent the closed end wall 4 of the trough 1, while a downwardly extending discharge chute 6 is formed integrally with the opposite end of the trough 1. The bottom 7 of the trough 1 slopes inwardly and downwardly from its opposite ends, and supports an outlet pipe 8 at its lowermost point.

A valve 9 is connected with the lower end of the outlet pipe 8, and a section of pipe 10 is connected at its upper end to the valve 9, while the lower end of the pipe 10 is connected with the upper end of a cylindrical retort 11. The upper end of the retort 11 is rounded as at 12, and the lower end of the retort 11 has a conical downwardly sloping closure 13, to which a valve 14 is connected.

A round collecting pot 15 is connected with the valve 14 for receiving and collecting the gold when separated by the amalgamator. A threaded plug 16 is threaded into the lower end of the pot 15, and will be removed when the gold in the pot 15 is to be removed.

A pair of outwardly and upwardly extending pipes 17 and 18 are connected at their lower ends with the rounded upper end 12 of the retort 11, and are connected at their upper ends with a condenser 19 disposed above the trough 1 and provided with an outlet 20, whereby the condensed mercury from the retort 11 will automatically flow back into the trough 1 to fill the bottom thereof to the desired and proper level.

A coil of pipe 21 will be disposed about the re-

retort 11 and will be connected with a suitable source of steam supply (not shown) for volatilizing the amalgam when let from the trough 1 through the valve 9 into the retort, to drive the vaporized mercury through the pipes 17 and 18 up into the condenser 19.

In Figure 1 of the drawings, there is shown a bearing 22 in the closed end wall 4 of the trough 1, and a cooperating bearing 23 supported by the bracket 24 adjacent the outlet or discharge end 10 of the trough 1.

A spiral screw 25 of larger dimension at its center and tapering towards its opposite ends is rotatably supported in the bearings 22 and 23, and a pulley wheel 26 is secured to the end of the screw 25 exteriorly of the bearing 22 whereby the screw may be rotated by a belt and prime mover (not shown).

In Figure 3 of the drawings, there is shown a pair of vertically disposed screws 27 and 28 of 20 a similar size rotatably mounted in the trough 1.

In Figure 4 of the drawings, there is shown a pair of vertically disposed screws 29 and 30 of 25 large and small size being rotatably mounted in the trough 1.

In Figures 5 and 6, there is shown a single screw 31 and a cooperating power driven movable chain 32 having spaced depending cross members 33 mounted at the top of the trough 1, whereby the screw 31 and cross member 33 will advance the 30 ore pulp from the inlet end of the trough towards the outlet end thereof.

In operation, mercury 34 will be received in the bottom of the trough 1, and ore pulp will be dumped into the inlet chute, to be stirred up and moved along the trough 1, so that the gold will be separated therefrom by the mercury, while the tailings will be discharged from the discharge chute. The amalgam which is the mercury and gold will be let into the retort 11 when the valve 40 9 is opened, and after the mercury has been volatilized by the heat from the steam in the pipe coil 21 surrounding the retort 11 and driven up into the condenser 19, the separated gold may be let into the pot 15 upon the opening of the 45 valve 14.

From the foregoing description, it will be ap-

parent that there has been devised and provided a highly efficient amalgamator.

While the preferred embodiment of the instant invention has been illustrated and described, it will be understood that it is not intended to limit the scope of the invention thereto, as many minor changes in detail of construction may be resorted to without departure from the spirit of the invention.

What is claimed is:

An amalgamator comprising an elongated U-shaped trough having a bottom sloping inwardly and downwardly from its opposite ends to the center thereof, a feed chute at one end of said trough and a discharge chute at the opposite end thereof, feed means comprising a spiral feed screw disposed horizontally within said trough directly under the feed chute, onto which material from the chute is delivered, a retort connected with the lowest point of said bottom, heating means disposed about said retort, a condenser, pipes connected with opposite sides of the retort at the top thereof, said pipes extending above the trough, said pipes being connected with said condenser at opposite sides thereof above the trough through which vaporized mercury passes to said condenser, and a pipe establishing communication between the condenser and trough whereby mercury in liquid form is delivered to the trough.

LEONELLO BRUNETTI.
